UNITED STATES PATENT OFFICE.

PATRICK F. GUTHRIE, OF NUTLEY, NEW JERSEY.

ROTARY ENGINE.

No. 801,662.

Specification of Letters Patent.

Patented Oct. 10, 1905.

Application filed January 12, 1905. Serial No. 240,678.

To all whom it may concern:

Be it known that I, PATRICK F. GUTHRIE, a citizen of the United States, and a resident of Nutley, in the county of Essex and State of New Jersey, have invented a new and Improved Rotary Engine, of which the following is a full, clear, and exact description.

The object of the invention is to provide a new and improved rotary engine which is simple and durable in construction, very effective in operation, and arranged to permit convenient reversing and to utilize the motive agent to the fullest advantage.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a side elevation of the improvement. Fig. 2 is an end view of the same. Fig. 3 is an enlarged cross-section of the same on the line 3 3 of Fig. 1. Fig. 4 is an enlarged sectional plan view of the improvement on the line 4 4 of Fig. 3, one of the exhausts being shown removed. Fig. 5 is a sectional side elevation of the same on the line 5 5 of Fig. 4. Fig. 6 is an enlarged sectional side elevation of one of the exhausts, the section being on the line 6 6 of Fig. 3. Fig. 7 is an enlarged sectional plan view of the same on the line 7 7 of Fig. 3. Fig. 8 is a perspective view of one of the abutments and the protection-valves for the same, and Fig. 9 is an enlarged cross-section of one of the abutment-stems and its lifting-arm.

In the cylinder A are mounted to turn a plurality of pistons B, secured to the main shaft C, extending through suitable stuffing-boxes in the cylinder-heads, the outer ends of the said main shaft C being journaled in suitable bearings carried by standards on the base or bed plate of the rotary engine. The pistons B are concentrically arranged in the cylinders A and snugly fit into the same, and each of the pistons is provided with an annular groove B' at its peripheral surface, the groove being approximately half-round, as indicated in Fig. 5, and across the groove extends a piston-head B², forming an integral part of the piston and against which the motive agent acts in

order to turn the piston B and the main shaft 55 C in either a forward or backward direction, as hereinafter more fully explained. The piston-heads B² are set at different angles one relative to the other, (see Fig. 3,) so that two of the pistons receive the motive agent under 60 full boiler-pressure at one time, while another is exhausted. It is, however, expressly understood that I do not limit myself to the number of pistons employed in a single cylinder, as the pistons may be increased in 65 number or two pistons or only a single piston used, if desired.

As the admission and exhaust of the motive agent to the cylinder and the grooves B' of the several pistons is the same in each case, it 70 is sufficient to describe but one in detail. Each of the grooves B' is adapted to be engaged by an abutment D, having its stem D' extending upward through a steam-chest E, and on the upper outer end of the stem D' is 75 journaled a friction-roller D², engaged at its under side by an arm F, secured to a shaft F', journaled in suitable bearings attached to the top of the steam-chest E. Each of the shafts F' is provided with an arm F², resting on top 80 of a friction-roller F³, journaled on the upper end of a rod F⁴, mounted to slide vertically in suitable bearings carried by the steam-chest E, and the lower end of the rod F⁴ is provided with a friction-roller F⁵ in peripheral 85 contact with a cam F⁶, secured on the main shaft C. When the engine is in operation and the main shaft C is rotated, then the several cams F⁶ successively actuate the rods F⁴, so as to slide the same upward, thereby imparting swinging motions to the arms F² to rock the shafts F', which by their arms F successively move the stems D' and the abutments D upward at the time the corresponding piston-head B² of a piston is approaching the 95 abutment, so that the latter is out of the way for the piston-head B² to pass. As soon as this has been done the corresponding abutment immediately slides back into its active position in the groove B', and for this purpose the upper end of the stem D' of each abutment is pressed on in a downward direction by a spring D³, held in a suitable casing D⁴, attached to the top of the steam-chest E.

It is understood that the cams F⁶ are so arranged on the main shaft C that they cause a raising of the abutments D in unison with the approach of the corresponding piston-

heads B^2 to allow the latter to pass at the proper time.

The motive agent is admitted to either one side or the other of each abutment D, according to the direction in which the engine is to run, and for this purpose each of the abutments is provided on opposite sides with inlet-ports a and b approximately U shape in form, as plainly indicated in Fig. 3. The motive agent from the steam-chest E is controlled previous to its passage to the ports a and b by protection-valves G and G', arranged on opposite sides of the corresponding abutment and mounted to slide in suitable chambers H and H', formed on the cylinder A, as plainly indicated in Fig. 3. The protection-valves G and G' have their valve-stems G² and G³ connected with each other by a cross-bar G⁴, secured to the corresponding abutment-stem D', so that the valves G and G' slide up and down in unison with the corresponding abutment D. The protection-valves G and G' are provided with transversely-extending ports c and d , adapted to register when the valves are in a lowermost position with ports e and f , with which register the upper ends of the ports a and b at the time the abutment D is in a lowermost position. The ports c and d also register when the valves G and G' are in a lowermost position with ports g and h , opening into chambers H² and H³, formed in the cylinder A adjacent to the chambers H and H' for the valves G and G'. The chambers H² and H³ are connected by ports i and j with the interior of the steam-chest E, connected with the boiler or other suitable source of motive-agent supply, the said ports i and j being formed in the bottom plate E' of the said steam-chest. The ports i and j are controlled by a manually-operated slide-valve I, mounted to slide transversely on the upper surface of the bottom plate E', and the said valve is so arranged that when the engine is in operation and the ports i are open then the ports j are closed, so that the motive agent can pass from the steam-chest E by way of the ports i , chambers H², and ports g , c , e , and a into the grooves B' of the several pistons to act on the piston-heads B² to drive the pistons B in the direction of the arrow x . When the slide-valve I is shifted manually to close the ports i and open the ports j , then the live steam or other motive agent can pass from the steam-chest E by way of the ports j into the chambers H³ and from the latter by way of the ports h , d , f , and b into the grooves B' at the other side of the abutment D to act on the piston-heads B² with a view to reverse the engine—that is, to rotate the piston B in the inverse direction of the arrow x . When it is desired to stop the engine, it is only necessary for the operator to shift the slide-valve I into an intermediate position—that is, to close both sets of ports i and j to cut off the motive agent from the cylinder.

In order to shift the slide-valve I into any one of the positions mentioned, the following device is provided: The front and rear sides of the slide-valve I are connected with rods I', extending through suitable stuffing-boxes to the front and rear walls of the steam-chest E, and the outer ends of the said rods I' are connected by a transverse bar I² with each other, the said bar being mounted to slide on the top of the steam-chest E, and on the middle portion of the bar is formed a rack I³, engaged by a segmental gear-wheel I⁴, attached to a shaft J, journaled in suitable bearings formed on a bracket secured to the top of the steam-chest E. On the shaft J (see Figs. 1 and 2) is secured a hand-lever J' under the control of the operator, and this hand-lever J' is provided with a pin J², adapted to engage one of a series of apertures in a segment J³ to hold the lever J' in either of three positions. When the lever J' is in the position shown in Figs. 1 and 2, then the slide-valve I is in the position shown in Fig. 3—that is, the ports i are open and the ports j are closed. When the operator swings the lever J' into an uppermost position, then the valve I is shifted transversely, so that the ports i are closed and the ports j are open, and when the lever J' is moved into an intermediate position then the slide-valve I closes both sets of ports i and j .

The exhaust of the motive agent from the cylinder and the grooves B' is controlled by exhaust-valves K and K', arranged on opposite sides of the cylinder A, the exhaust-valves having casings K² and K³, connected by ports k and k' with the interior of the cylinder at the grooves B'. In the valve-casings K² and K³ are mounted to slide vertically slide-valves K⁴ and K⁵ to open and close the ports k and k' , respectively—that is, when one of the ports is closed the other is open—the slide-valves being controlled from the shaft J and lever J' to move the slide-valve K⁵ into an open position at the time the slide-valve I uncovers the ports i and closes the ports j . When the slide-valve I is reversed, as previously mentioned, and the ports i are closed and the ports j are open, then the valves K⁴ are moved into a closed position and the valves K⁵ into an open position to allow the exhaust to take place by way of the exhaust-valve K'. The slide-valves K⁴ and K⁵ have their valve-stems K⁶ and K⁷ pivotally connected with rods L and L', mounted to slide vertically in suitable bearings carried by the steam-chest E, and the upper ends of the said rods L and L' are provided with racks L² and L³ in mesh with opposite sides of segmental gear-wheels L⁴, secured on the shaft J. When the latter is rocked by the operator manipulating the lever J', as previously described, then a simultaneous sliding motion in opposite directions is given to the rods L and L' to shift the slide-valves K⁴ and K⁵ simultaneously and in unison.

with the movement given to the slide-valve I, as previously explained. Thus from the foregoing it will be seen that when the slide-valve I is in the position shown in Fig. 3 the exhaust takes place by way of the exhaust-valve K, and when the valve I is shifted to close the ports *i* and open the ports *j* then the exhaust takes place by way of the exhaust-valve K'.

The operation is as follows: When the valves I, K, and K' are in the position shown in Fig. 3, then the steam passes from the steam-chest E into the cylinder and the several grooves B' at the left-hand side of the abutments D to rotate the pistons B in the direction of the arrow *x*, it being understood that each abutment D is raised and with it its protection-valves G and G' whenever the corresponding piston-head approaches the abutment in question. It is evident that when the protection-valves G and G' of an abutment D are lifted they cut off the steam from the abutment, as the ports *c* and *d* move out of register with the ports *g* *h* and *e* *f*, and consequently steam is not liable to leak from the chambers H² and H³ through the ports *a* and *b* of the abutment and into the cylinder. Thus the valves G and G' afford protection against leakage of steam, and hence it is not necessary to use expensive and cumbersome packing devices at the abutments. The motive agent entering a groove B' of a piston B acts on the piston-head B² thereof until the piston-head B² is closing the corresponding exhaust-port *k*, and when the piston-head B² reaches this position the abutment D and its protection-valves G and G' begin to rest, so as to cut off the motive agent from the corresponding groove B' and to allow the motive agent behind the piston-head B² to exhaust through the port *k* and casing K². By the time the piston-head B² reaches a top position the corresponding abutment D has moved into its uppermost position to allow the piston-head to pass, and then the abutment D immediately returns to its lowermost position to again bring the valves G and G' into proper register with their ports and also to bring the ports *a* and *b* of the abutments D in register with the ports *e* and *f*. When the engine is reversed, as previously stated, the motive agent passes into the cylinder by way of the port *b* to cause the piston to rotate in the reverse direction of the arrow *x* and to exhaust by way of the exhaust-valve K'.

Having thus described my invention, I claim as new and desire to secure by Letters Patent—

1. A rotary engine comprising a cylinder, a piston fitted therein and having an annular groove in its periphery and a piston-head extending across the groove, an abutment adapted to slide in and out of the said groove, said abutment having a stem and provided with an inlet-port, mechanism connected with the stem of the abutment for imparting a sliding motion to the said abutment in unison with the rotation of the piston, to allow the piston-head to pass

the abutment, and a steam-chest connected with the said abutment-ports at the time the abutment is in an active position.

2. A rotary engine comprising a cylinder, a piston fitted therein and having an annular groove in its periphery and a piston-head extending across the groove, an abutment adapted to slide in and out of the said groove and provided with an inlet-port, means for imparting a sliding motion to the said abutment in unison with the rotation of the piston, to allow the piston-head to pass the abutment, a steam-chest connected with the said abutment-ports at the time the abutment is in an active position, and a protection-valve moving with the abutment and arranged in the connection between the abutment and the steam-chest.

3. A rotary engine comprising a cylinder, a plurality of concentric pistons fitted therein and having annular grooves in their peripheries and piston-heads extending across the grooves, the several piston-heads being set at angles one to the other, slidable abutments for the said grooves, each having inlet-ports on opposite faces, means for imparting movement to the said abutments in unison with the pistons, to allow the piston-heads to pass the abutments, a steam-chest having sets of ports for connection with the inlet-ports in the abutments, and a manually-controlled slide-valve in the said steam-chest, to control the sets of steam-chest ports.

4. A rotary engine comprising a cylinder, a plurality of pistons fitted therein and having annular grooves in their peripheries and piston-heads extending across the grooves, the several piston-heads being set at angles one to the other, slidable abutments for the said grooves, each having inlet-ports on opposite faces, means for imparting movement to the said abutments in unison with the pistons, to allow the piston-heads to pass the abutments, a steam-chest having sets of ports for connection with the inlet-ports in the abutments, a manually-controlled slide-valve in the said steam-chest, to control the sets of steam-chest ports, and exhaust-valves for controlling the exhaust from the said grooves, the said exhaust-valves moving in unison with the said slide-valve.

5. A rotary engine comprising a cylinder, a plurality of pistons fitted therein and having annular grooves in their peripheries and piston-heads extending across the grooves, the several piston-heads being set at angles one to the other, slidable abutments for the said grooves, each having inlet-ports on opposite faces, means for imparting movement to the said abutments in unison with the pistons, to allow the piston-heads to pass the abutments, a steam-chest having sets of ports for connection with the inlet-ports in the abutments, a manually-controlled slide-valve in the said steam-chest, to control the sets of steam-chest ports, exhaust-valves on opposite sides of the

cylinder, and means under the control of the operator, for simultaneously shifting the slide-valve and the said exhaust-valves in unison.

6. A rotary engine comprising a cylinder, 5 a plurality of pistons fitted therein and having annular grooves in their peripheries and piston-heads extending across the grooves, the several piston-heads being set at angles one to the other, slidable abutments for the said grooves, each having inlet-ports on opposite faces, means for imparting movement to the said abutments in unison with the pistons, to allow the piston-heads to pass the abutments, a steam-chest having sets of ports 10 for connection with the inlet-ports in the abutments, a manually-controlled slide-valve in the said steam-chest, to control the sets of steam-chest ports, exhaust-valves on opposite sides of the cylinder, and means under the control of the operator for simultaneously shifting the slide-valve and the said exhaust-valves in unison, 15 the said means comprising a rock-shaft, a hand-lever for operating the rock-shaft, segmental gear-wheels on the rock-shaft, a rack connected with the said slide-valve and in mesh with one of the said segmental gear-wheels and sliding rods connected with the stems of the exhaust-valves and having racks in mesh 20 between the abutment-ports and the said steam-chest ports.

7. A rotary engine comprising a cylinder, a plurality of pistons fitted therein and having annular grooves in their peripheries and 25 piston-heads extending across the grooves, the several piston-heads being set at angles one to the other, slidable abutments for the said grooves, each having inlet-ports on opposite faces, means for imparting movement 30 to the said abutments in unison with the pistons, to allow the piston-heads to pass the abutments, a steam-chest having sets of ports for connection with the inlet-ports in the abutments, a manually-controlled slide-valve in 35 the said steam-chest, to control the sets of steam-chest ports, protection-valves for the abutments, arranged in the port connections between the abutment-ports and the said steam-chest ports, and means supporting the 40 protection-valves directly from the abutment-stems.

8. A rotary engine comprising a cylinder, a plurality of pistons fitted therein and having annular grooves in their peripheries and 45 piston-heads extending across the grooves, the several piston-heads being set at angles one to the other, slidable abutments for the said grooves, each having inlet-ports on opposite faces, means for imparting movement 50 to the said abutments in unison with the pistons, to allow the piston-heads to pass the abutments, the said means consisting of rock-shafts having arms engaging the spring-pressed abutment-stems, slide-rods engaged 55 by other arms on the said rock-shafts and cams on the piston-shaft, engaging the said slide-rods, a steam-chest having sets of ports for connection with the inlet-ports in the abutments, and a manually-controlled slide-valve 60 in the said steam-chest, to control the sets of steam-chest ports.

9. A rotary engine comprising a cylinder, a plurality of pistons fitted therein and having annular grooves in their peripheries and piston-heads extending across the grooves, the 65

several piston-heads being set at angles one to the other, slidable abutments for the said grooves, each having inlet-ports on opposite faces, means for imparting movement to the said abutments in unison with the pistons, to 70 allow the piston-heads to pass the abutments, a steam-chest having sets of ports for connection with the inlet-ports in the abutments, a manually-controlled slide-valve in the said steam-chest, to control the sets of steam-chest 75 ports, exhaust-valves on opposite sides of the cylinder, and means under the control of the operator for simultaneously shifting the slide-valve and the said exhaust-valves in unison, the said means comprising a rock-shaft, a hand-lever for operating the rock-shaft, segmental gear-wheels on the rock-shaft, a rack connected with the said slide-valve and in mesh with one of the said segmental gear-wheels and sliding rods connected with the stems of the exhaust-valves and having racks in mesh 80 between the abutment-ports and the said steam-chest ports.

10. In a rotary engine, a cylinder, a piston in the cylinder and provided with a piston-head, a sliding abutment having a stem and 90 provided with ports, a slotted casing in which projects the stem of the abutment, a spring in the casing and surrounding the abutment-stem, a rock-shaft provided with an arm in engagement with the stem of the abutment 95 within the casing, and means for operating the rock-shaft from the piston-shaft.

11. In a rotary engine, a cylinder, a piston in the cylinder and provided with a piston-head, a sliding abutment having a stem and 100 provided with ports, a slotted casing in which projects the stem of the abutment, a spring in the casing and surrounding the abutment-stem, a rock-shaft provided with arms, one of which projects through the casing and into 105 engagement with the stem of the abutment, a sliding rod engaged by the other arm of the rock-shaft, and a cam carried by the piston-shaft and operating said sliding rod.

12. In a rotary engine, a cylinder, a piston in the cylinder and provided with a piston-head, a sliding abutment having a stem and 110 provided with ports, means for imparting sliding motion to the abutment in unison with the piston, a protection-valve having a stem, 115 and a connection between the stem of the protection-valve and the stem of the abutment.

13. In a rotary engine, a cylinder, a piston in the cylinder and having a piston-head, a 120 slidable abutment having inlet-ports, means for imparting movement to the abutment in unison with the piston, a steam-chest having ports, a slide-valve in the steam-chest, a rack connected at its ends with the slide-valve, a segmental gear-wheel meshing with the rack, 125 and means for operating said gear-wheel.

14. In a rotary engine, a cylinder, a piston in the cylinder and having a piston-head, a sliding abutment, means for moving the abutment in unison with the piston, a steam-chest, 130

a slide-valve in the steam-chest, a rock-shaft, means for operating the slide-valve for the rock-shaft, sliding exhaust-valves, sliding rods provided with racks and connected with the exhaust-valves, and segmental gear-wheels carried by the rock-shaft and engaging the racks of the sliding rods.

In testimony whereof I have signed my name to this specification in the presence of two subscribing witnesses.

PATRICK F. GUTHRIE.
